DIESTERS OF SATURATED ALIPHATIC DICARBOXYLIC ACIDS CONTAINING BOTH OXYGEN AND SULPHUR IN THE CHAIN

John R. Dann, Peter P. Chiesa, and William G. Lovett, Rochester, N.Y., assignors to Eastman Kodak Company, Rochester, N.Y., a corporation of New Jersey No Drawing. Original application Oct. 14, 1959, Ser. No. 846,230, now Patent No. 3,038,805, dated June 12, 1962. Divided and this application May 24, 1962, Ser. No. 197,274

6 Claims. (Cl. 260—481)

This application is a division of our application Serial No. 846,230, filed October 14, 1959 (now U.S. Patent No. 3,038,805, issued June 12, 1962).

This invention relates to photographic silver halide emulsions, and more particularly, to an improved means for sensitizing such photographic silver halide emulsions.

A number of methods have been previously described for increasing the sensitivity of photographic silver halide emulsions, other than methods of optical or spectral sensitization, which involve the incorporation of certain colored compounds or dyes in the emulsions. The incorporation of such dyes in the emulsions increases the optical range of sensitivity, and for this reason such dyes are commonly referred to as optical or spectral sensitizing dyes. It is also well known to increase the sensitivity of photographic emulsions by addition of sulfur compounds capable of reacting with silver salts to form silver sulfide, or with reducing agents (compounds of these types are also naturally present in gelatin), or with salts of gold or other noble metals, or with combinations of two or more of the aforementioned compounds generally known as chemical sensitizers. Such chemical sensitizers are believed to react with the silver halide to form, on the surface of the silver halide, minute amounts of silver sulfide or of silver or of other noble metals, and these processes are capable of increasing the sensitivity of developing-out emulsions by very large factors. The process of chemical sensitization, however, reaches a definite limit beyond which further addition of sensitizers, or of further digestion with the sensitizers present, merely increases the fog of the photographic emulsion with constant or decreasing speed.

We have now found a means of further increasing the sensitivity of photographic emulsions which may be applied even though the ordinary processes of chemical sensitization have been carried to the effective limit of the photographic emulsion in question. Our process is to be distinguished from hypersensitization, which is produced by bathing a finished coating with water or with solutions of ammonia, amines or silver salts. Such processes act primarily on optically sensitized photographic emulsions and tend to increase the free silver ion concentration of the emulsion and greatly diminish its stability. Our process is also to be distinguished from hypersensitization by mercury vapor, which gives a transitory effect which is lost on storage of the film. The compounds used in our invention do not appear to be chemical sensitizers in the usual sense, since they increase speed by their presence during exposure and processing and require no digestion with the photographic emulsion to produce an increase in speed, nor does their chemistry indicate that they are likely to react with silver halide under normal emulsion conditions.

The novel sensitizers of our invention are quite unique in that the effects produced are additive in photographic emulsions which have already been sensitized to their optimum, or near-optimum, with conventional chemical sensitizers, such as labile sulfur compounds. The novel sensitizers of our invention, however, can be used to sen-

2

sitize photographic silver halide emulsions containing no other sensitizers, if desired. The novel sensitizers of our invention are not strictly chemical sensitizers, since chemical sensitizers do not generally provide the additive effects of the type mentioned.

It is, therefore, an object of our invention to provide photographic silver halide emulsions which have been sensitized with various non-polymeric compounds containing a plurality of sulfur atoms. Another object of our invention is to increase the sensitivity of ordinary photographic silver halide emulsions which have been sensitized with chemical sensitizers, such as compounds containing labile sulfur atoms, or gold-containing compounds. Other objects will become apparent from a consideration 15 of the following description and examples.

According to our invention, we have found that the sensitivity of an ordinary photographic silver halide emulsion can be materially increased by incorporating therein non-polymeric open-chain compounds, which can be characterized as polyoxathioethers. These non-polymeric compounds contain their sulfur atoms in the form of thioether linkages. By thioether linkages, we mean a linkage wherein the sulfur atom is divalent and is joined to two non-oxocarbonyl carbon atoms. Compounds useful in sensitizing photographic silver halide emulsions according to the present invention are to be distinguished from the polymeric thioether compounds described in U.S. patent application Serial No. 779,874, filed December 12, 1958, by J. R. Dann and J. J. Chechak (now U.S. Patent 3,046,134, issued July 24, 1962). The polymeric compounds described in this latter application are generally characterized as having high molecular weights and as containing characteristic repeating units or groups.

The sensitizing compounds useful in practicing our invention are non-polymeric and can be represented by the following general formula:

wherein R represents a member selected from the class 45 consisting of hydroxyl, alkoxy containing from 1 to 4 carbon atoms and carbamyl radicals, R₁ represents a member selected from the class consisting of hydrogen and methyl, each of X₁ and X₂ is a different divalent radical selected from the class consisting of oxygen and sulfur atoms, m is an integer of from 0 to 1 and n is an integer of from 0 to 2. Typical alkoxy radicals (R) include methoxyl, ethoxyl, propoxyl, butoxyl, etc.

The compounds of Formula I above can be prepared according to methods which have been previously described in the technical literature. For example, these compounds can be prepared by condensing together a monothiol with a dihalogenated ether compound in the presence of sufficient alkali to form the alkali metal salt of the monothiol. Alternatively, these compounds can be prepared by condensing together an organic halide with sodium sulfide. These two alternative methods of syntheses can be outlined as follows:

METHOD A

65 The reaction of a mercaptan with a dihalide

METHOD B

70 The reaction of a halide with sodium sulfide

The compounds of Formula I above, wherein R represents a carbamyl group, can be prepared according to the following method:

METHOD C

In the above exemplary reactions, R defines the non-reactive portions of the molecule and does not have the definitions assigned above for this group.

These methods of syntheses are illustrated in the following examples:

Example 1.—Preparation of 1,14-dihydroxy-6,9-dioxa-3,12-dithiatetradecane

2-mercaptoethanol, 15.6 g. (0.2 mole), and 1,2-bis(2-chloroethoxy)ethane, 18.7 g. (0.1 mole) were dissolved in 50 ml. of ethanol and mixed with 50 ml. of water containing 0.1 mole of sodium carbonate. The reaction mixture was heated under a reflux condenser on the steam bath for 20 hours, the solvent removed under vacuum, and the product separated from the sodium chloride formed, by extraction with hot absolute ethanol and ethyl acetate. The solvents were removed from the combined extracts and the product was distilled. B.P. 220–230°C./3 mm.

Analysis.—Calcd. for $\text{C}_{10}\text{H}_{22}\text{S}_2\text{O}_4$: C, 44.4; H, 8.1; S, 23.7; mol. wt., 270. Found: C, 44.5; H, 8.0; S, 23.3; mol. wt., 277.

Example 2.—Preparation of 3,6,12,18,21-pentoxa-9,15-dithiatricosane

A mixture of 5.3 g. (0.05 mole) of sodium carbonate, 6.9 g. (0.05 mole) of bis mercaptoethyl ether, and 19.7 g. (0.1 mole) of ethoxyethoxyethyl bromide in 60 ml. of 50 percent ethanol was refluxed on a steam bath overnight. Most of the ethanol was stripped off with a water aspirator, the residual material was extracted with ethyl acetate, and the extracts were dried over anhydrous sodium sulfate. Removal of the ethyl acetate and distillation in vacuum gave the product boiling at 214–218°C./1 mm.

Analysis.—Calcd. for $\text{C}_{15}\text{H}_{34}\text{O}_5\text{S}_2$: C, 51.9; H, 9.2; S, 17.3. Found: C, 52.0; H, 9.2; S, 17.6.

Example 3.—Preparation of 3,6,12,15-tetraoxa-9-thiaheptadecane

This compound was prepared according to the method described in Example 5 below, using sodium sulfide nonahydrate dissolved in water and ethoxyethoxyethylbromide in ethanol.

Example 4.—Preparation of 2,8,11,17-tetraoxa-5,14-dithiaoctadecane

A mixture of 2.3 g. (0.1 mole) of sodium, 9.1 g. (0.05 mole) of 1,2-bis(2-mercaptoethoxy)ethane and 13.9 g. (0.1 mole) of methoxyethyl bromide in 100 ml. of ab-

solute ethanol was refluxed on a steam bath for 2½ hours, after which the solvent was stripped off with a water aspirator, and the residue was extracted with three 50-ml. portions of hot ethyl acetate. The extracts were dried over anhydrous sodium sulfate, the solvent was removed and the residue distilled in vacuum to give the product boiling at 174°C./1 mm.

Analysis.—Calcd. for $\text{C}_{12}\text{H}_{26}\text{O}_4\text{S}_2$: C, 48.3; H, 8.7; S, 21.5. Found: C, 48.4; H, 8.7; S, 21.4.

Example 5.—Preparation of 3,6,9,15,18,21-hexao-12-thiatricosane

A solution of 9 g. (0.0375 mole) of sodium sulfide nonahydrate in 25 ml. of water, and 18.1 g. (0.075 mole) of ethoxyethoxyethoxyethyl bromide in 50 ml. of ethanol was refluxed with a water aspirator, till cloudiness appeared, after which the mixture was extracted with ethyl acetate. Drying the extract over anhydrous sodium sulfate, followed by removal of the ethyl acetate and distillation in vacuum gave a product boiling at 172°C./1 mm.

Analysis.—Calcd. for $\text{C}_{16}\text{H}_{34}\text{O}_6\text{S}$: C, 54.3; H, 9.6; S, 9.0; mol. wt., 354. Found: C, 53.8; H, 9.7; S, 9.1; mol. wt., 336.

Example 6.—Preparation of 3,9,12,18-tetraoxa-6,15-dithiaeicosane

Following the procedure of Example 1 above, using 5.3 g. (0.05 mole) of sodium carbonate, 9.1 g. (0.05 mole) of 1,2-bis(2-mercaptoethoxy)ethane, and 15.3 g. (0.1 mole) of ethoxyethyl bromide in 50 percent ethanol, a product was obtained which boiled at 172–174°C./1½ mm.

Analysis.—Calcd. for $\text{C}_{14}\text{H}_{30}\text{O}_4\text{S}_2$: C, 51.5; H, 9.2; S, 19.7; mol. wt. 326. Found: C, 51.0; H, 9.0; S, 19.6; mol. wt., 335.

Example 7.—Preparation of 3,9,15-trioxa-6,12-dithiaheptadecane

Following the procedure of Example 1 above, using 2.65 g. (0.025 mole) of sodium carbonate, 3.45 g. (0.025 mole) of bis mercaptoethyl ether and 7.65 g. (0.05 mole) of ethoxyethyl bromide in 50 percent ethanol, a product was obtained which boiled at 147°C./2 mm.

Analysis.—Calcd. for $\text{C}_{12}\text{H}_{26}\text{O}_3\text{S}_2$: C, 51.0; H, 9.2; S, 22.7. Found: C, 50.3; H, 8.9; S, 23.5.

Example 8.—3,6,15,18-tetraoxa-9,12-dithiaeicosane

Following the procedure of Example 1 above, using 5.3 g. (0.05 mole) of sodium carbonate, 4.7 g. (0.05 mole) of ethane dithiol, and 19.7 g. (0.1 mole) of ethoxyethoxyethyl bromide in 50 percent ethanol, a product was obtained which boiled at 172–173°C./2½ mm.

Analysis.—Calcd. for $\text{C}_{14}\text{H}_{30}\text{O}_4\text{S}_2$: C, 51.5; H, 9.2; S, 19.7. Found: C, 51.1; H, 8.9; S, 19.4.

Example 9.—Preparation of 1,17-dihydroxy-3,9,15-trioxa-6,12-dithiaheptadecane-4,14-dione

A mixture of 2.65 g. (0.025 mole) of sodium carbonate, 3.45 g. (0.025 mole) of bis mercaptoethyl ether, and 9.15

4. The compound represented by the following formula:

5. The compound represented by the following formula:

6. The compound represented by the following formula:
